CAM LAPING MACHINE

Herbert S. Indge, Westboro, Mass., assignor to
Norton Company, Worcester, Mass., a corpora-
tion of Massachusetts

Application June 7, 1943, Serial No. 489,907

12 Claims. (Cl. 51—64)

This invention relates to abrading machines, and more particularly to a cam lapping machine.

One object of the invention is to provide a simple and thoroughly practical lapping machine for simultaneously lapping a plurality of cams. A further object of the invention is to provide an automatic cam lapping machine with a plurality of lapping arms each of which is provided with a continuous strip of abrasive lapping paper. A further object of the invention is to provide a cam lapping machine with an automatic continuous abrasive paper feed which continuously presents a fresh abrading surface for the lapping operation.

A further object of the invention is to provide an automatic cam lapping machine in which the work support for the cams to be lapped together with the lapping arms are automatically and simultaneously reciprocated. Another object of the invention is to provide a lapping machine in which the initial lapping operation is produced while the cams to be lapped are rotated and the cams together with the lapping arms are simultaneously reciprocated and the abrading lapping paper is automatically and continuously fed for a predetermined time interval. A further object of the invention is to provide an automatic mechanism for stopping the paper feed and stopping the lapping arm reciprocation after a predetermined lapping operation to facilitate a finish lapping operation.

Another object of the invention is to provide an automatic cam lapping machine which is arranged to produce a controlled lapping operation for a predetermined period of time during which interval the abrasive paper is automatically and continuously fed and the lapping arms and the work pieces are automatically reciprocated for a predetermined initial lapping operation after which the lapping operation proceeds for a final or finish lapping operation during which period the lapping arm reciprocation is stopped and the abrasive paper feeding mechanism is stopped for a predetermined period of time. A further object of the invention is to provide an automatic cam lapping machine in which an electric time delay relay serves to control an initial lapping operation during which operation the cams to be lapped are rotated and reciprocated, the lapping arms are also reciprocated and the abrasive lapping paper automatically fed, the electrical time relay serving after a predetermined time interval to stop the lapping arm reciprocations, the abrasive paper feed and to set in motion a second electrical time delay relay which con-

trols the final or finish lapping operation and which serves after a predetermined time interval to move the lapping arms automatically to an inoperative position to stop the work drive motor to move the footstock center to an inoperative position. Other objects will be in part obvious or in part pointed out hereinafter.

The invention accordingly consists in the features of construction, combinations of elements, and arrangements of parts, as will be exemplified in the structure to be hereinafter described, and the scope of the application of which will be indicated in the following claims.

In the accompanying drawings in which is shown one of various possible embodiments of the mechanical features of this invention,

Fig. 1 is a front elevation of the improved cam lapping machine;

Fig. 2 is a right hand end elevation, on a reduced scale of the machine shown in Fig. 1;

Fig. 3 is a combined hydraulic and electrical diagrammatic illustration of the control mechanism of the improved cam lapping machine;

Fig. 4 is a longitudinally vertical sectional view, on an enlarged scale, taken through the headstock spindle;

Fig. 5 is a fragmentary elevation, on an enlarged scale, showing the chain drive for synchronously rotating the machine cam shaft with the work spindle;

Fig. 17 is a fragmentary plan view, on an enlarged scale, taken approximately on the line 17-17 of Fig. 2 showing the lapping arm assembly;

Fig. 18 is a right hand end elevation, on an enlarged scale, of one of the lapping arms taken approximately on the line 18-18 of Fig. 17;

Fig. 19 is a fragmentary sectional view, on an enlarged scale, taken approximately on the line 19-19 of Fig. 17, showing the details of construction of the yieldable nose of one of the cam lapping arms;

Fig. 20 is a fragmentary horizontal sectional view taken approximately on the line 20-20 of Fig. 18 showing the abrasive paper feed rolls;

Fig. 21 is a fragmentary plan view, on an enlarged scale, taken approximately on the line 21-21 of Fig. 22 showing the abrasive lapping rolls and the tensioning and feeding mechanism;

Fig. 22 is a fragmentary right hand elevation, on an enlarged scale, taken approximately on the line 22-22 of Fig. 20 showing the arrangement of the abrasive lapping paper feed rolls and the indexing mechanism;

Fig. 23 is a front elevation of a modified arrangement of the work supporting arbor as shown in Fig. 1;

Fig. 24 is a fragmentary sectional view, on an enlarged scale, taken approximately on the line 24-24 of Fig. 1 through the control lever and associated mechanism; and

Fig. 25 is a fragmentary sectional view through the actuating mechanism for the footstock center as shown in Fig. 3.

A lapping machine has been illustrated in the drawings in which a machine base 20 supports a longitudinally movable work supporting table 21. A rotatable work support is provided on the table 21 including a headstock 22 and a footstock 23. The headstock 22 supports a rotatable headstock spindle 24 in bearings 25 and 26. The headstock spindle 24 is provided with a driving mechanism such as for example an electric motor 27 having a built-in speed reduction gear unit. The electric motor 27 is provided with a multiple V-groove pulley 28 which is drivingly connected by multiple V-belts 29 with a multiple V-groove pulley 30. The pulley 30 is fixedly supported on a shaft 31 which is journaled in bearings (not shown) in the headstock 22. A worm 33 is keyed to the shaft 31 and meshes with a worm gear 34 which is keyed to the headstock spindle 24.

The right hand end of the headstock spindle 24 is provided with a work engaging and driving member 35 which is arranged to support and drive the end of a work supporting arbor 36. The work

supporting arbor 36 is arranged to support a plurality of aeroplane cams 37 and 38 to be lapped.

The footstock 23 is provided with a footstock center 40 which is rotatably supported within a slidably mounted sleeve 41 within the footstock 23. A hydraulically operated mechanism is provided for moving the footstock center 40 to and from an operative position to support the right hand end of the work supporting arbor 36. This mechanism may comprise a fluid pressure cylinder 42 which contains a slidably mounted piston 43. A piston rod 44 is connected at one end to the piston 43. The other end of piston rod 44 is pivotally connected to a link 45. The link 45 is in turn pivotally connected to a pivotally mounted bell crank lever 46. The other end of the bell crank lever 46 is connected by means of a stud 47 with a link 48. The link 48 is pivotally connected to a slidably mounted sleeve 49. A compression spring 50 is contained within the sleeve 49 and serves yieldably to maintain footstock center 40 in operative position when the bell crank lever 46 and the link 48 are swung to an operative position.

The work supporting table 21 is preferably arranged so that it may be reciprocated during a lapping operation to impart a reciprocatory movement to the cams being lapped. A connecting rod 53 is provided having one end pivotally supported on the stud 52. The other end of the connecting rod 53 is connected to a stud 54 which is integrally formed on one end of a rotatable stud 55, the stud 54 being eccentrically formed relative to the axis of rotation of the stud 55. The upper end of the stud 55 is provided with a spiral gear 56 which meshes with a spiral gear 57 mounted on the right hand end of a rotatable shaft 58. The shaft 58 serves as a support for a gear 59 which in turn meshes with a gear 60. The gear 60 is integral with the worm gear 34 which is keyed to the headstock spindle 24. It will be readily apparent from the foregoing disclosure that rotation of the headstock spindle 24 will be imparted through the gear 60, the gear 59, the spiral gears 57-56 to rotate the stud 55 and that imparts a rotary motion to the eccentric stud 54 which in turn will serve to impart a reciprocatory motion to the work supporting table 21 through the connecting rod 53.

50 Lapping arm support

It is desirable to provide a movable support for a plurality of lapping arms so that they may be simultaneously and quickly moved to and from an operative position. A pair of spaced arms 62 and 63 are mounted on a rock shaft 64 (Fig. 2) which is supported in bearings on the rear of the machine base 20. The arms 62 and 63 are provided with horizontally extending portions which are connected by two spaced parallel bars or slide rods 65 and 66 which serve as slide rods or ways for supporting a plurality of lapping arms to be hereinafter described.

The lapping arm assembly supported by the arms 62 and 63 is arranged so that it may be automatically moved to and from an operating position to facilitate loading of cams to be lapped into the machine and removing them therefrom after a lapping operation has been completed. In order to move the entire lapping arm assembly to and from an operative position, a fluid pressure mechanism is provided including a fluid pressure cylinder 68 which is pivotally connected by means of a stud 69 with the base 20 of the machine. A piston 70 is slidably mounted with-

in the cylinder 68 and is connected at one end to a piston rod 71. The other end of the piston rod 71 is connected by a stud 72 with an arm 73 pivotally mounted on a shaft 74 within the base 20 of the machine. The other end of the arm 73 is connected by a stud 75 to one end of a link 76 connected by stud 77 with a toggle lever 78. The adjacent ends of the toggle lever 78 and a toggle lever 79 are connected by a stud 80. The toggle lever 78 is connected at its other end by means of a stud 81 which is fixedly mounted relative to the base 20. The toggle lever 79 is connected by a stud 82 with an arm 83 which is fixedly mounted on the rock shaft 64 and is arranged to rock the shaft 64 together with the arms 62 and 63 and all of the lapping arms together with their supporting and actuating mechanism either to or from an operative position.

The lever as shown in full line positions in Fig. 2, are in a position to hold the arm 83 together with the arms 62 and 63 and the entire lapping arm assembly in an operative position. When a lapping operation is started, fluid under pressure is admitted to the cylinder 68 to cause the piston 70 to move downwardly (Fig. 3) and the piston rod 71 to move toward the left (Fig. 2) to shift the levers 73, 76, 78, 79 and arm 83 into the broken line positions indicated in Fig. 2 to move the entire lapping arm assembly to an operative position.

A pair of slides 90 and 91 are slidably supported on the rods 65 and 66. The slide 90 serves as a support for a plurality of lapping arms 92, 93, 94, and 95. The slide 91 serves as a support for a plurality of lapping arms 96, 97, 98 and 99. In addition to reciprocating the work supporting table 21 it is desirable to impart a reciprocatory movement to the lapping arms during a lapping operation. In the preferred construction, a reciprocating mechanism is provided to simultaneously reciprocate the slide 90 and 91 in the opposite direction so as to impart the secondary reciprocatory motion between the lapping element and the cam being lapped. A motor driven reciprocating mechanism is provided comprising an adjustably mounted electric motor 100 which is supported on a platen 101 which is fixedly supported on the rock shaft 64 and is arranged to move with the arms 62 and 63 toward and from an operative position. The motor 100 is provided with a V-groove pulley 102 which is connected by a V belt 103 with a pulley 104 which is mounted on one end of a rotatable shaft 105. The shaft 105 is rotatably supported in single pillow block bearings 106 and 107 which are adjustably supported on the platen 101. The shaft 105 is provided with a multiple V-groove pulley 108 which is connected by multiple V-belts 109 with a multiple V-groove pulley 110 which is mounted on one end of a rotatable shaft 111. The shaft 111 is provided with a pair of eccentrics 112 and 113 (Fig. 8) which are connected by connecting rods 114 and 115 respectively, with studs 116 and 117. The studs 116 and 117 are fixedly mounted on the slides 90 and 91, respectively. It will be readily apparent from the foregoing disclosure that when the motor 100 is set in motion, a simultaneous reciprocatory movement will be imparted in opposite directions to the slides 90 and 91 to impart a reciprocatory movement to the lapping arms.

Master cams

In order to produce a controlled movement of the lapping arms, it is desirable to provide a

master cam for controlling the transverse movement of each of the lapping arms. A master cam shaft 120 is rotatably supported by bearings 121 and 122 which are in turn supported in fixed relationship with the arms 62 and 63 respectively.

The master cam shaft 120 is preferably driven in synchronism with the headstock spindle 24. The headstock spindle 24 is provided with a keyed sprocket 123 which is connected by a link roller chain 124 with a sprocket 125. The sprocket 125 is rotatably supported on an extension of the trunnion shaft 64. An adjustable, rotatably mounted idler sprocket 126 is provided to facilitate tensioning the roller chain 124. A sprocket 127 is mounted to rotate with the sprocket 125 and is connected by means of a link chain 128 with a sprocket 129 which is mounted on the end of the master cam shaft 120. An adjustably mounted idler sprocket 130 is provided to facilitate tensioning of the driving chain 128. It will be apparent from the foregoing disclosure that rotation of the headstock spindle 24 will be transmitted through the chain drive above described synchronously to rotate the master cam shaft 120. By driving from the headstock 22 to the trunnion shaft 64 and then from the trunnion shaft 64 to the master cam shaft 120, a synchronous drive of the work arbor 36 and the master cam shaft 120 will be obtained in any position of the lapping arm assembly.

The master cam shaft 120 is provided with a plurality of master cams 132, 133, 134, 135, 136, 137, 138 and 139. These master cams are formed in pairs which are integral with each other as illustrated in cross section in Fig. 16. The lapping arms 92, 93, 94, 95, 96, 97, 98 and 99 are provided with adjustably mounted offset follower rollers 140, 141, 142, 143, 144, 145, 146 and 147, respectively, which serve to transmit the motion of the master cams to the lapping arms. The lapping arms are provided with an offset nose piece 148, 149, 150, 151, 152, 153, 154, and 155 which are offset to facilitate a close relationship between the nose pieces to simultaneously lap a pair of adjacent cams (Fig. 17).

The lapping arms 92, 93, 94, 95, 96, 97, 98 and 99 are arranged so that they may be moved transversely as controlled by the master cams above described. Tension springs 156, 157, 158, 159, 160, 161, 162, and 163 are provided to exert a force on the transversely movable lapping arms to maintain the follower rollers in operative engagement with the master cams as the lapping operation proceeds and to impart a simultaneous controlled movement to the lapping arms (Fig. 16).

Each of the lapping arms 92, 93, 94, 95, 96, 97, 98, and 99 is supported for a transverse movement by means of a plurality of rollers 164, 165, 166, 167, 168 and 169 (Fig. 18). Each of the lapping arms is supported in an adjustable frame 170 (Fig. 18) which is provided with a dove-tailed surface 171 which mates with the correspondingly shaped surface on the upper portion of the slides 90 and 91 respectively. It will be readily apparent from this disclosure that the frames 170 carrying the lapping arms 92, 93, 94, 95, 96, 97, 98, and 99 may be readily adjusted relative to the slides 90 and 91 respectively, to position the lapping arms as desired.

Abrasive paper feed

An independent roll of continuous flexible abrasive paper 175, 176, 177, 178, 179, 180, 181 and 182 is provided for each of the lapping arms. The

rolls of abrasive paper are pivotally supported on a shaft 183 (Figs. 18) which is in turn supported by upwardly extending brackets 184 and 185 (Fig. 15), which are fixedly supported relative to the lapping arm assembly.

As shown in Fig. 18 a strip of abrasive paper 186 from the roll of paper 182 passes downwardly around the yieldable nose piece 155 on the lapping arm 99 and passes upwardly over a rod 206 and over a knurled feed roller 187 which is rotatably supported on a shaft 188 supported between the brackets 184 and 185 and passes downwardly between the periphery of the feed roller 187 and a feed roller 189 which is rotatably supported on a shaft 190. The shaft 190 is also supported by the brackets 184 and 185. A pair of gears 191 and 192 are fixedly mounted on the feed rollers 187 and 189 so that the two feed rollers 187 and 189 are rotated together to feed abrasive paper strip 186 therebetween. As illustrated in Fig. 21 the abrasive paper feed rollers are arranged integrally in pairs, a similar set of feed rollers 193 and 194 being formed integral with the feed rollers 187 and 189. A ratchet wheel 195 is fixedly mounted relative to the feed rollers 187 and 193. A holding pawl 196 is supported by the shaft 190 and serves to hold the ratchet wheel 195 against rotation in a counterclockwise direction (Fig. 22). An actuating pawl 197 engages the ratchet wheel 195 and is pivotally supported by a stud 198. The stud 198 is supported at one end of an arm 199 which is clamped onto the shaft 188. It will be readily apparent that an oscillating motion of the shaft 188 will be transmitted to turn the ratchet wheel 195 in a clockwise direction (Fig. 22) to advance the abrasive paper 186 so as to present a fresh portion of abrading material across the nose 155 of the lapping arm 99.

A similar set of feed rollers 200 are provided for feeding abrasive paper from the abrasive paper rolls 175 and 176 to the lapping arms 92 and 93 respectively. A similar set of feed rollers 201 are provided for feeding abrasive paper from the abrasive paper rolls 177 and 178 to the lapping arms 94 and 95. A set of feed rollers 202 are provided to feed abrasive paper from the abrasive paper rolls 179 and 180 to the lapping arms 96 and 97 respectively. The feed rollers 200, 201 and 202 together with their actuating mechanisms are identical with that previously described (Figs. 21 and 22), consequently these mechanisms have not been illustrated and described in detail.

The feed rollers 200, 201 and 202 are opposed by feed rollers 203, 204, and 205 which are rotatably supported on the shaft 188.

In order to maintain a yieldable pressure between the feed rollers to index abrasive paper therebetween, the shaft 188 is preferably yieldably supported. A plurality of brackets 207, 208, 209, 210 and 211 are fixedly clamped on the shaft 120. The other ends of the brackets 207, 208, 209, 210 and 211 are fixedly clamped on the rod 206. The opposite ends of the shaft 188 are supported in bearings 212 and 213 which are in turn slidably supported in the brackets 184 and 185 respectively and compression springs 214 and 215 are provided normally to urge the shaft 188 toward the shaft 190. Each of the brackets 207, 208, 209, 210 and 211 is provided with a slidably mounted bearing block 216 (Fig. 14) which serves as an intermediate support for the shaft 188. Compression springs 217 are provided in each of the brackets 207, 208, 209, 210, and 211 to maintain a pressure urging the shaft 188 towards the

shaft 190 thus to maintain a yieldable pressure between the opposed abrasive paper feed rollers above described. The details of only one of the brackets 211 are shown in Fig. 14. All of the other brackets 207, 208, 209 and 210 are identical in construction and consequently have not been illustrated in detail. Each of the brackets is provided with a slidably mounted stud 219 one end of which engages the slideable bearing block 216 and the other end of which engages an eccentric 218. If it is desirable to release the tension between the feed rollers, the levers 220, 220a, 220b, 220c, and 220d may be rocked in a counterclockwise direction (Fig. 14) to shift the eccentric 218 so as to move the slidably mounted bearing blocks 216 and shaft 188 away from the shaft 190 and thus separate the sets of feed rollers.

Hydraulic Motor

In order to automatically and simultaneously actuate the pawl and ratchet abrasive paper feeding mechanism above described, a mechanism is provided for oscillating the shaft 188 simultaneously to index all of the abrasive paper to provide a continuous feeding of the abrasive paper during the lapping operation. This mechanism may comprise a self-contained fluid motor 225 which has been illustrated in section in Fig. 3 but will not be described in detail since this motor is identical with that shown in the prior United States patent to Wallace H. Wood, 2,212,871, dated August 27, 1940, to which reference may be had for details of disclosure not contained herein. The fluid motor 225 includes a cylinder 226 having a slideable piston 227 which is provided with a piston rod 228. The piston rod 228 is connected to a downwardly projecting arm 229 the upper end of which is fixedly clamped to the shaft 188. The fluid motor 225 is provided with a combined pilot and reversing valve 230 which is arranged to continuously reciprocate the piston 227 when fluid under pressure is passed through a pipe 231 from a source to be herein-after described. It will be readily apparent that a continuous reciprocation of the piston 227 will impart a continuous oscillation to the shaft 188 which in turn serves to actuate simultaneously a two part pawl 197 on each of the arms 199 of the sets of feed rollers, simultaneously to impart a continuous feeding movement to the flexible abrasive lapping paper. In case it is desired to stop the automatic feed of the abrasive paper on any one or more of the lapping arms, the feed pawls 197 (Fig. 22) may be rocked in a clockwise direction to an inoperative position so that the oscillating motion of the shaft 188 will not impart a feeding movement to the abrasive paper passing between the adjacent feed rollers.

Hydraulic controls

A hydraulically operated control mechanism is provided for controlling the various elements of the machine. A motor driven fluid pressure pump 235 is provided for drawing fluid through a pipe 236 from a reservoir 237 and passing fluid under pressure through a pipe 238 to a stop and start valve 239 (Fig. 3). A pressure relief valve 240 is provided to facilitate passing excess fluid under pressure from the system directly to the reservoir 237. The valve 240 is a standard variable pressure relief valve and consequently has not been illustrated in detail. The stop and start valve 239 is a piston type valve comprising a valve stem 241 having a plurality of valve

pistons formed integrally therewith. In the position of the valve 239 (Fig. 3) fluid under pressure passing through the pipe 238 passes outwardly through a pipe 242 into an end chamber 243 in a piston type control valve 244. The piston type control valve 244 comprises the valve stem 245 having a plurality of valve pistons formed integrally therewith. A chamber 246 of the valve 244 is connected by a pipe 247 with the stop and start valve 239 and as shown in Fig. 3 is connected so as to exhaust fluid from the chamber 246 through a passage 248 and a pipe 249 into the reservoir 237. It will be readily apparent from the foregoing disclosure that the start and stop valve 239 serves to control the admission of fluid to and from the end chambers 243 and 246 of the control valve 244 to shift the valve stem 245 either toward the right (Fig. 3) into the position illustrated in the drawings at the end of the lapping cycle or to shift the valve stem 245 toward the left (Fig. 3) to initiate a lapping cycle. An adjustable valve 250 is provided in the pipe line 249 to facilitate controlling the exhaust of fluid from the end chambers 243 and 246 of the control valve 244 so as to control the rate of movement of the valve stem 245 when it is moved in either direction.

The control valve 244 is operatively connected to control the admission of fluid under pressure to the cylinder 68 to cause a movement of the lapping arm assembly to and from an operative position, and to the cylinder 42 to actuate the footstock center 40.

The control valve 244 is provided with valve chambers 255, 256 and 257. The valve chamber 255 is connected by a pipe 258 with a chamber 259 formed in the upper end of the cylinder 68. The chamber 256 of the valve 244 is connected by a pipe 260 with a chamber 261 formed at the lower end of the cylinder 68. A combined check and throttle valve 262 is provided in the pipe line 260 which is arranged to allow substantially unrestricted passage of fluid through the pipe 260 when fluid under pressure is admitted to the cylinder chamber 261 to cause the lapping arm assembly to move to an inoperative position, but is arranged so that a desired controlled rate of movement may be obtained when the lapping arm assembly is moved to an operating position.

Similarly the valve chamber 255 is connected by a pipe 263 with a cylinder chamber 264 in the cylinder 42. The valve chamber 256 is connected by a pipe 265 with a chamber 266 formed in the cylinder 42. It will be readily apparent from the foregoing disclosure that the control valve 244 serves to control the admission to or exhaust of fluid from the opposite ends of the cylinder 42 to actuate the footstock center 40.

The valve chamber 256 of the control valve 244 is connected by a pipe 268 to the pipe 238 which is directly connected with the pump 235 so that fluid under pressure is continually admitted to the valve chamber 256. The pipe 268 is also connected with a pipe 269 which is in turn connected with the pipe 231 to supply fluid under pressure for actuating the fluid motor 225. A normally closed valve 270 is provided between the pipe 231 and 269 which serves as a stop and start valve to stop the fluid motor 225 automatically, as will be hereinafter described, during the lapping cycle. An electric pull type solenoid 271 is provided which is arranged when energized to open the valve 270 and thus to start the fluid motor 225. Fluid is exhausted from the combined pilot and reversing valve 230 of the fluid

motor 225 through a pipe 272 and through an adjustable throttle valve 273 by means of which speed of movement of the fluid motor 225 may be regulated. Fluid exhausts from the control valve 244 through a passage 274 and passes through an exhaust pipe 275 into the reservoir 237. The pipe 272 which exhausts fluid from the fluid motor 225 is connected to the exhaust pipe 275.

10 An interlock mechanism is provided which cooperates with the movement of the control valve 244 to prevent the movement of the lapping arm assembly into an operative position before the footstock center 40 is moved into operative engagement to position a work piece to be lapped. This mechanism comprises a flange 279 which is fixedly mounted adjacent to the rear end of the valve stem 245. A spring pressed detent 280 normally lies in the path of the flange 279. The detent 280 is connected by means of a flexible cable 281 with the bell crank lever 46. When fluid under pressure is passed into the cylinder chamber 264 to rock the bell crank lever 46 in a clockwise direction to move the footstock center 40 into an operative position, this motion moves the cable 281 to withdraw the detent 280 out of the path of the flange 279. It will be readily apparent from the foregoing disclosure that unless the footstock center 40 has moved into an operative position, the valve stem 245 cannot be shifted toward the left a sufficient distance to admit the fluid under pressure through the pipe 258 to cause a downward movement of the piston 70 to move the lapping arm assembly into an operative position.

15 A similar spring-pressed detent 282 is provided which lies in the path of the flange 279 during a lapping operation. The detent 282 is connected to a pivotally mounted bell crank lever 283 the upper end of which is connected by a flexible cable 284 (Fig. 2) with the arm 63. The detent 282 serves to prevent a movement of the flange 279 and valve stem 245 toward the right to prevent withdrawal of the footstock center 40 before the lapping arm assembly has been moved to an inoperative position.

20 A manually operable control lever 285 is fixedly mounted on the outer end of a rock shaft 286. A downwardly extending arm 287, mounted on the inner end of the rock shaft 286, is connected by a stud 288 to the upper end of a link 289. The lower end of the link 289 is connected by a stud 290 to the valve stem 241. When it is desired to shift the start and stop valve 239 to initiate a lapping cycle, the control lever 285 is shifted in a counterclockwise direction into the broken line position 285a (Fig. 3), which movement is transmitted through the rock shaft 286, the arm 287 and the link 289 to cause a downward movement of the valve stem 241 which shifts the valve pistons of the valve 239 downwardly so that fluid under pressure is passed from the pressure line 238, through the pipe 247, into the end chamber 246 of the control valve 244 to move the valve toward the left (Fig. 3).

25 The control lever 285 is provided with a downwardly extending integral arm 291 which is connected by a stud 292 to one end of a link 293. The link 293 is connected at its other end to an armature 294 of a pull type solenoid 295. When the solenoid 295 is energized, it causes the armature 294 and link 293 to move toward the left (Fig. 3) into the position illustrated. This movement shifts the arm 291 and the control lever 285 in a clockwise direction, from position 285a

into full line position 285, to stop the cycle at the end of the lapping operation. The solenoid 295 is energized automatically, as will be hereinafter described, to terminate the lapping operation after a predetermined time interval has elapsed.

The arm 291 is provided with an integral downwardly extending projection 296 which is arranged to engage and move an actuating plunger 297 of a normally open limit switch 298 so as to close the limit switch when the control lever 285 is shifted in a counterclockwise direction into broken line position 285a for the start of a lapping cycle.

A normally closed limit switch 300 is provided with an actuating roller 301 which lies in the path of an arm 302 (Fig. 3). The arm 302 is fixedly mounted on the arm 62 of the lapping arm assembly. The arm 302 is arranged so that when the lapping arm assembly is in an inoperative position, the normally closed limit switch 300 is automatically opened so as to prevent starting of the headstock motor 27.

A magnetic starter switch 305 is provided to control the starting and stopping of the forward or normal lapping rotation of the headstock motor 27. A magnetic reverse switch 306 is operatively connected through a motor brake switch 307 (Figs. 1 and 3) to reverse the flow of current to the headstock motor 27 and through the motor brake switch 307 rapidly to stop it after the desired time interval. A similar magnetic starter switch 308 is provided for controlling the forward or normal rotation of the lapping arm reciprocating motor 100 and a magnetic reverse switch 309 is provided to control the reversal of the current to the motor 100. A motor brake switch 310 is operatively connected with the motor 100 which serves rapidly to stop the rotation of the motor 100 when it is desired to stop the reciprocating movement of the lapping arm assembly.

In order to automatically control the lapping cycle a pair of electrical time delay relays 311 and 312 are provided. These relays are shown diagrammatically in Fig. 3 and may be any of the standard commercial instantaneous reset timers which are in common use in the machine tool field. As illustrated in Fig. 3, a relay known commercially as "Microflex" instantaneous reset timer, manufactured by the Eagle Signal Corporation, may be employed.

The time relay 311 is so connected in the electrical system that when the control lever 285 is shifted in a counterclockwise direction to start the lapping cycle, the valve stem 241 is moved down so as to admit fluid under pressure to the pipe 247 to cause the valve stem 245 to move toward the left (Fig. 3) at the same time the normally open switch 298 is closed. During the initial shifting movement of the valve stem 245, fluid is admitted through the pipe 263 into the cylinder chamber 264 to actuate the footstock center to move it into operative engagement with the work supporting arbor 36, after which fluid is admitted to the cylinder chamber 259 of the cylinder 68 to cause a movement of the lapping arm assembly toward an operative position. During the movement of the lapping arm assembly, the arm 202 (Figs. 2 and 5) moves away from the roller 301 and allows the normally closed switch 300 which is in series with the limit switch 298 to close. Closing of the limit switch 300 serves through the starter switch 305 to start the headstock motor 27 and at the same time sets the time relay 311 in motion to energize the starter switch 308 and starts the motor 100 to reciprocate

the lapping arms and also energizes the solenoid 271 and opens the valve 270 to operate the fluid motor 225. When the fluid pressure pump 235 is started, the fluid is transmitted through the pipe

5 238, 268, 269 and 231 to actuate the fluid motor 225 when the solenoid 271 is energized by the time relay 311, to automatically operate the paper feeding mechanism continuously to feed abrasive paper. The individual paper indexing mechanisms are operative only when their actuating pawls are shifted to operative positions in engagement with the ratchet wheels previously described. The lapping operation proceeds for a predetermined time interval as governed by the time relay 311 during which time the headstock for the work drive motor 27 rotates the work supporting arbor 36, and at the same time reciprocates it in an axial direction. The rotary motion of the work drive motor is also transmitted through the link chain drive previously described synchronously to rotate the master camshaft 120 so as to impart a controlled motion to the lapping arms. After a predetermined time interval has elapsed, as governed by the time relay 311, the lapping arm reciprocating motor 100 is stopped and at the same time solenoid 271 is deenergized to allow the valve 270 to close, thus stopping the automatic continuous feeding of the abrasive lapping paper so that a final or finish lapping operation is obtained during which time the work rotates and reciprocates while the lapping paper is maintained stationary so as to produce a final lapping operation on the work piece. At the same time as the time relay 311 operates 15 to stop the paper feed and the lap arm reciprocation, it operates to set in motion the second time relay 312 which is connected to govern the final or finish lapping operation. After a predetermined time interval as governed by the time relay 312, the solenoid 295 is energized to shift the control lever 285 from the broken line position 285a (Fig. 3) into the full line position 285 to shift the stop and start valve stem 241 into the extreme upper position, which movement in turn 20 serves to shift the valve stem 245 of the control valve 244 toward the right into the position illustrated in Fig. 3. When the control lever 285 is shifted to the full line position, the limit switch 298 is opened so that the headstock motor 27 will 25 be stopped at the end of the lapping cycle. During this shifting movement fluid under pressure is admitted to the cylinder 68 to cause the lapping arm assembly to move to an inoperative position. Movement of the lapping arm assembly to an 30 inoperative position serves to open the normally closed limit switch 300 which in turn serves to prevent starting the work drive motor 27 while the lapping arms are in an inoperative position. Shifting of the valve stem 245 then allows the 35 hydraulic power to actuate the footstock 23 to remove the footstock center 40 from operative supporting engagement with the work supporting arbor 36.

A push button switch 314 is mounted on the 40 front of the machine base 20 and is operatively connected to control the stopping and starting of the motor driven fluid pump 235.

The sets of cams 37 and 38 to be lapped are formed integrally in pairs on an annular shaped 45 member such as used in the modern airplane motor. In order to support these rim-shaped cams, special clamping flanges 316 and 317 are mounted on the work supporting arbor 36 which serves to center and locate the product cams 50 with respect to the work supporting arbor 36. A

driving plate 318 having a centering projection is provided at the left-hand end of the work supporting arbor 36 to locate and drive the arbor in a predetermined position with respect to the driving member 35 of the headstock spindle 24 and also to drive the arbor 36 during the lapping operation. Due to the annular ring-shaped cams 37 and 38 to be lapped, it is preferable to lap two sets of cams at one time, as shown in Fig. 1 of the drawings. During this lapping operation, the operator may load a second work supporting arbor 36a which is provided with locating, supporting and clamping flanges 319 and 320 for supporting and locating product cams similar to the clamping flanges 316 and 317. It should be noted that on the first lapping operation when the work supporting arbor 36 is placed in operative position in the machine, lapping arms 92 and 93 are arranged to engage and lap the cam 37, and the lapping arms 94 and 95 are arranged to lap the cam 38. On the next lapping operation using the second work supporting arbor 36a, it should be noted that the flanges 319 and 320 are spaced closer together, so that on the second lapping operation the lapping arms 94 and 95 are operative to lap the cam 37a and the lapping arms 96 and 97 are arranged to perform a lapping operation of the cam 38a. During each of the lapping operations, two pairs of lapping arms are inoperative and the paper feed on these lapping arms is rendered inoperative by shifting the index pawls 197 associated with each of the arms 199 to an inoperative position.

Operation

The operation of this improved lapping machine will be readily apparent from the foregoing disclosure. Two sets of work pieces to be lapped are clamped in position on the work supporting arbor 36 which is placed in a loading position on a pair of spaced work supporting arbor cradles 321 and 322 (Figs. 1 and 2) after which the work arbor 36 is rolled into position with the work arbor 36 in alignment with the headstock work driving spindle 24 and the footstock center 40. The push button 314 is then actuated to start the fluid pump 235 and a knife switch 315 is closed to render the electrical circuits of the machine ready for a lapping operation. The main control lever 285 is then shifted manually in a counterclockwise direction (Figs. 1 and 3) to shift the stop and start valve 239 to a starting or down position which admits fluid under pressure through the pipe 247 to cause the control valve 244 to move toward the left (Fig. 3) to initiate a lapping cycle. The shifting movement of the control valve 244 toward the left serves first to admit fluid through the pipe 263 to actuate the footstock center 40 so as to move it into operative supporting engagement with the work arbor 36 after which fluid is admitted through the pipe 258 to the cylinder 68 to move the lapping arm assembly to an operative position. The movement of the control lever 285 to a starting position serves to close the normally open limit switch 298 and the movement of the lapping arm assembly serves to close the normally closed limit switch 300 which closes a series circuit to start the work drive motor 27 and at the same time to set the time relay 311 in motion to start the motor 100 to impart a reciprocating movement to the pair of slides 90 and 91 which support the lapping arms so as to impart a relative reciprocating movement to the lapping

arms and energize the solenoid 271 to set the fluid motor 225 into motion to impart an oscillating motion to the abrasive paper feeding mechanism previously described. The lapping operation proceeds until a predetermined time interval has elapsed as governed by the time relay 311 which serves to simultaneously stop the motor 100 thus stopping the reciprocation of the lapping arms, at the same time the solenoid 271 is deenergized to close the valve 270 to stop the fluid motor 225 thereby stopping the automatic continuous feed of the abrasive paper, and at the same instant the time relay 312 is set in motion to govern the final or finish lapping operation. After a predetermined final or finish lapping operation is produced, during which time the abrasive lapping paper is held stationary and the lapping arms are not reciprocated, the time relay 312 operates to energize the solenoid 295 to shift the control lever 285a in a clockwise direction into full line position (Fig. 3) to initiate a movement of the electrical and hydraulic controls to an inoperative position. At the same time, the stop and start valve 239 is moved upwardly into the position shown in Fig. 3 which serves to admit fluid under pressure through the pipe 242 to the end chamber 243 to move the valve stem 245 toward the right into the position illustrated in Fig. 3 during which time the lapping arm assembly is moved to an inoperative position. Movement of the lapping arm assembly to an inoperative position serves to open the limit switch 300, as previously described. The fluid under pressure is then admitted to the footstock cylinder chamber 266 to withdraw the footstock center 40. The work arbor 36 may then be removed from the machine and the work arbor 36a placed in position for the next lapping operation.

It will be readily apparent from the foregoing disclosure that the preliminary or initial lapping operation may be automatically controlled by the setting of the time relay 311 and the duration of the final or finish lapping operation may be readily controlled by manipulation of the time relay 312, thus providing an automatic cycle of operation, it being only necessary for the operator to initiate the cycle by shifting the main control lever 285 into the position 285a.

It will thus be seen that there has been provided by this invention apparatus in which the various objects hereinabove set forth together with many thoroughly practical advantages are successfully achieved. As many possible embodiments may be made of the above invention and as many changes might be made in the embodiment above set forth, it is to be understood that all matter hereinbefore set forth or shown in the accompanying drawings is to be interpreted as illustrative and not in a limiting sense.

I claim:

1. In a cam lapping machine having a base, means including a rotatable motor driven headstock spindle to rotate a camshaft, a rotatable master cam, a synchronous drive between said spindle and master cam, a slidably mounted lapping arm, a follower on said arm which engages said master cam, means including a motor to reciprocate said lapping arms during a lapping operation, and an electrical control system including an electrical time delay relay which is operatively connected after a predetermined time interval to stop said lapping arm reciprocation and thereafter to stop the rotation of said head-

stock spindle after a lapping operation has been completed.

2. In a cam lapping machine having a base, means including a motor driven headstock spindle to rotate a camshaft, a rotatable master cam which is synchronously rotated with said spindle, a slidably mounted lapping arm, a follower on said arm in operative engagement with said master cam, a continuous strip of abrasive lapping paper on said arm, means automatically and continually to feed said lapping paper during a lapping operation, and an electrical control system including an electric time delay relay which is operatively connected after a predetermined time interval to stop said paper feed and thereafter to stop said headstock spindle after a predetermined lapping operation has been completed.

3. In a cam lapping machine having a base, a rotatable motor driven headstock spindle to rotate a camshaft, a rotatable master cam which is synchronously rotated with said spindle, a slidably mounted lapping arm having a follower in operative engagement with said master cam, means including a motor to reciprocate said lapping arms, and an electrical control system including an electric time delay relay which is operatively connected after a predetermined time interval to stop said motor and lap arm reciprocation for a final lapping operation, and means thereafter to stop said headstock spindle after a predetermined final lapping operation has been completed.

4. In a cam lapping machine having a base, a rotatable motor driven headstock spindle to rotate a camshaft, a rotatable master cam which is synchronously rotated with said spindle, a continuous strip of abrasive lapping paper on said arm, means including a motor automatically and continuously to feed said lapping paper during a lapping operation, and an electrical control system including an electric time delay relay which is operative after a predetermined time interval to stop said motor and paper feed for a final lapping operation, and means thereafter to stop said headstock spindle after a predetermined lapping operation has been completed.

5. In a cam lapping machine having a base, a rotatable motor driven headstock spindle to rotate a camshaft, a rotatable master cam synchronously rotated with said spindle, a slidably mounted lapping arm having a follower in operative engagement with said master cam, means to reciprocate said lapping arm, a continuous strip of abrasive lapping paper on said arm, means automatically and continually to feed said lapping paper during a lapping operation, and an electrical control system including an electric time delay relay which is operatively connected after a predetermined time interval to stop said lapping arm reciprocation and said paper feed after a predetermined lapping operation to facilitate a final lapping operation.

6. In a cam lapping machine having a base, a rotatable motor driven headstock spindle to rotate a camshaft, a rotatable master cam which is synchronously rotated with said spindle, a slidably mounted lapping arm having a follower in operative engagement with said master cam, means including a motor to reciprocate said lapping arms, a continuous strip of abrasive lapping paper on said arms, means including a motor automatically and continually to feed said lapping paper during a lapping operation, and an electrical control system including an electric time delay relay which is operatively connected

after a predetermined time interval to stop said motors so as to stop the lap arm reciprocation and to stop the abrasive paper feed after a predetermined initial lapping operation to facilitate a final lapping operation.

7. In a cam lapping machine having a base, a rotatable motor driven headstock spindle to rotate a camshaft, a rotatable master cam which is synchronously rotated with said spindle, a slidably mounted lapping arm having a follower in operative engagement with said master cam, means including a motor to reciprocate said lapping arm, a continuous strip of abrasive lapping paper on said arms, means including a motor actuated pawl and ratchet automatically and continuously to feed said lapping paper during a lapping operation, an electrical control system including an electric time delay relay which is operatively connected after a predetermined time interval to stop said motors so as to stop the lapping arm reciprocation and to stop the abrasive paper feed after a predetermined initial lapping operation to facilitate a final lapping operation, and a second electric time delay relay which is rendered operative by said first time relay after the initial lapping operation has been completed which is operatively connected after a predetermined final lapping operation to stop said headstock spindle.

8. In a cam lapping machine having a base, a rotatable camshaft support thereon to support a plurality of cams to be lapped, means including a headstock spindle to rotate said cams, a rotatable master camshaft having a plurality of master cams thereon, a synchronous drive between said headstock spindle and said master camshaft, a plurality of slideable lapping arms, a follower on each of said lapping arms which is in operative engagement with one of said master cams, means including a motor to reciprocate said lapping arms in a direction parallel to the axis of said cams, a continuous strip of abrasive lapping paper on each of said lapping arms, a pawl and ratchet feed mechanism on each of said arms continuously to feed said abrasive paper during a lapping operation, means including a motor operatively connected simultaneously to actuate a plurality of said feeding mechanisms, and an electrical control system including an electric time delay relay which is operatively connected to stop said motors after a predetermined lapping operation so as to stop said lapping arm reciprocation and to stop said abrasive paper feed to facilitate a final lapping operation.

9. In a cam lapping machine having a base, a rotatable camshaft support thereon to support a plurality of cams to be lapped, means including a headstock spindle to rotate said cams, a rotatable master camshaft having a plurality of master cams thereon, a synchronous drive between said headstock spindle and said master camshaft, a plurality of slideable lapping arms, a follower on each of said lapping arms which is in operative engagement with one of said master cams, means including a motor to reciprocate said lapping arms in a direction parallel to the axis of said cams, a continuous strip of abrasive lapping paper on each of said lapping arms, a pawl and ratchet feed mechanism on each of said arms continuously to feed said abrasive paper during a lapping operation, means including a motor operatively connected simultaneously to actuate a plurality of said feeding mechanisms, an electrical control system including an electric time delay relay which is operatively

connected to stop said motors after a predetermined lapping operation so as to stop said lapping arm reciprocation and to stop said abrasive paper feed to facilitate a final lapping operation, and means including a second electric time relay which is rendered operative by said first time relay after the initial lapping operation has been completed which is operatively connected after a predetermined final lapping operation to stop said headstock spindle.

10. In a cam lapping machine having a base, a rotatable motor driven headstock spindle to rotate a camshaft, a rotatable master cam which is synchronously rotated with said spindle, a slidably mounted lapping arm having a follower in operative engagement with said master cam, means to move said lapping arm to and from an operative position, means including a motor to reciprocate said lapping arm, a continuous strip of abrasive lapping paper on said arms, means including a motor actuated pawl and ratchet automatically and continuously to feed said lapping paper during a lapping operation, an electrical control system including an electric time delay relay which is operatively connected after a predetermined time interval to stop said motors so as to stop the lapping arm reciprocation and to stop the abrasive paper feed after a predetermined initial lapping operation to facilitate a final lapping operation, and a second electric time delay relay which is rendered operative by said first time relay after the initial lapping operation has been completed which is operatively connected after a predetermined final lapping operation to stop said headstock spindle, and to move said lapping arm to an inoperative position.

11. In a cam lapping machine having a base, a rotatable motor driven headstock spindle to rotate a camshaft, a rotatable master cam which is synchronously rotated with said spindle, a slidably mounted lapping arm having a follower in operative engagement with said master cam, means including a fluid motor to move said lapping arm to and from an operative position, means including a motor to reciprocate said lapping arm, a continuous strip of abrasive lapping paper on said lapping arms, means including a motor actuated pawl and ratchet automatically and continuously to feed said lapping paper during a lapping operation, a solenoid valve to control said motor actuated pawl and ratchet, an electrical control system including an electrical

- time delay relay which is operatively connected after a predetermined time interval to stop said lap arm reciprocating motor and to actuate said solenoid valve so as to stop the lap arm reciprocation and to stop the abrasive paper feed after a predetermined initial lapping operation to facilitate a final lapping operation, and a second electric time delay relay which is rendered operative by said first time relay after the initial lapping operation has been completed which is operatively connected after a predetermined final lapping operation to stop said headstock spindle and to move said lapping arm to an inoperative position.
15. 12. In a cam lapping machine having a base, a rotatable camshaft supported thereon to support a plurality of cams to be lapped, means including a headstock spindle to rotate said cams, a rotatable master camshaft having a plurality of master cams thereon, a synchronous drive between said headstock spindle and said master camshaft, a movable lap arm assembly having a plurality of slidably mounted lapping arms thereon, a follower on each of said lapping arms which is in operative engagement with one of said master cams, means including a fluid motor to move said lap arm assembly to and from an operative position, means including a motor to reciprocate said lapping arms in a direction parallel to the axis of said cams, a continuous strip of abrasive lapping paper on each of said lapping arms, a pawl and ratchet feed mechanism associated with each of said arms continuously to feed said abrasive paper during a lapping operation, means including a motor operatively connected simultaneously to actuate a plurality of said feeding mechanisms, an electrical control system including an electrical time delay relay which is operatively connected to stop said lap arm reciprocating motor and to stop said abrasive paper feed motor after a predetermined lapping operation so as to stop said lap arm reciprocation and to stop said abrasive paper feed to facilitate a final lapping operation, and means including a second electrical time relay which is rendered operative by said first time relay after the initial lapping operation has been completed which is operative after a predetermined final lapping operation to stop said headstock spindle and to admit fluid under pressure to the lap arm assembly motor to move said assembly to an inoperative position.

HERBERT S. INDGE.
